UNITED STATES PATENT OFFICE.

GEORGE I. GALITZKA, OF NEW YORK, N. Y.

LISTENING-IN SIGNAL FOR TELEPHONE APPARATUS.

1,360,632.

Specification of Letters Patent. Patented Nov. 30, 1920.

Application filed February 20, 1917. Serial No. 149,718.

To all whom it may concern:

Be it known that I, GEORGE I. GALITZKA, a citizen of the United States, and a resident of New York, borough of Manhattan, in the county of New York and State of New York, have made and invented certain new and useful Improvements in Listening-in Signals for Telephone Apparatus, of which the following is a specification.

10 My invention relates to the art of telephony, and particularly to an apparatus for producing a warning signal in the subscriber's line that the local switchboard operator's circuit is connected to the subscriber's line and that the operator is listening-in.

15 A most frequent cause of complaint from apartment houses and other places where a local switchboard is maintained, is the listening-in of the operator and her subsequent repeating of that which she has heard. It is accordingly an object of my invention to provide an apparatus which will prevent the local switchboard operator from listening-in, the desired end being attained without in any wise interfering with the local operator receiving instructions or conversing with the subscribers, as desired. In accomplishing the foregoing, I have provided an apparatus which will 20 sound a warning signal in the subscriber's receiver and in the receiver of the local switchboard operator immediately upon connecting in the subscriber's line the local operator's circuit. The warning signal may be in the nature of a faint, but audible, buzzing noise, and is only sufficient to remind the subscribers that their conversation is being listened to, and to notify the local operator of the fact that the subscribers are 25 aware of her listening-in. The local switchboard operator, realizing that a warning signal will be sounded when her circuit is connected in the subscriber's line, the moral effect will thus prevent the operator from 30 listening-in.

35 With the above and other objects in view, and with the aim to attain the aforementioned ends in a simple and expeditious manner, and with a view of not in any wise interfering with the various circuits and operations of the telephone, my invention resides in the combination and arrangement of parts, and in the details of construction hereinafter described and claimed, it being 40 understood that changes in the precise em-

bodiment of the invention may be made within the scope of what is claimed without departing from the spirit thereof.

The preferred embodiment of my invention is disclosed in the accompanying drawings, wherein:

Figure 1 is a view in perspective of a telephone switchboard such as is used in apartment houses, hotels, etc., where considerable trouble has been experienced, due to the 65 listening-in of the local switchboard operator:

Fig. 2 is a diagrammatic view of the electric circuits whereby a warning signal is mechanically produced in the subscriber's 70 circuit that the local operator is listening-in;

Fig. 3 is a diagrammatic view similar to the foregoing, wherein the warning signal is electrically produced in a subscriber's 75 circuit.

Referring specifically to the several views, and particularly to Fig. 2, the local operator's circuit 10 includes a plurality of the usual type of keys 11, which are arranged 80 for connecting the local operator's circuit 10, with its transmitter 12 and receiver 13, into the subscriber's line.

In order that a warning signal will be produced in the subscriber's line A when the 85 key 11 is depressed and the operator's circuit thus connected in the subscriber's line circuit and the local switchboard operator listening-in, the moving element 15, of the operator's listening-in switch and key 11, is provided 90 with an insulated metallic projection 16. Spaced contact points 17 are arranged beneath, and adapted to be bridged by, the projection 16 when the listening-in key 11 is depressed. An electric circuit 20 is connected 95 to the contact points 17, (which latter accordingly act as a switch) and includes a source of electrical energy 18 and an electric buzzer 19. The electric buzzer 19 is contained within the switchboard 21, and the noise produced thereby when the operator's listening-in key is depressed is sufficient to impress a warning signal upon the operator's transmitter 12 and so notify the subscribers that their conversation is being listened to. The 105 warning signal may be accentuated and magnified by placing a supplemental transmitter 22 directly in front of the electric buzzer, should it be so desired.

Other ways of mechanically producing a 110

warning signal in the local operator's transmitter when the listening-in key is depressed will readily suggest themselves to those skilled in the art, and I therefore do not limit myself to the exact arrangement as above described.

As illustrating a manner in which the warning signal may be electrically impressed upon the subscriber's line circuit, reference is had to Fig. 3 of the drawings, wherein I have provided an electric circuit 23 which includes a circuit breaker 24, capable of intermittently making and breaking the circuit, and a source of electrical energy 25. The electric circuit 23 is directly connected to the local operator's transmitter circuit 26. The operator's listening-in keys 11' are provided with the insulated projections 16', which are adapted to complete the circuit 23 across the spaced points 17'. With this arrangement, should the operator fail to return the listening-in key to its upright position after the subscriber has obtained the desired party, the prolonged action of the circuit breaker 24, by impressing either an intermittent or variable electromotive force upon the local operator's circuit, will accordingly warn and notify the subscribers that their conversation is being listened to. The local operator, however, realizing that the sub-

scribers are aware of her listening-in, will be prevented from so doing.

What I claim is:—

In a telephone apparatus of the class described, the combination with a local operator's switchboard of a local operator's circuit including a transmitter and receiver, listening-in key switches adapted to connect the local operator's circuit to a subscriber's line circuit, supplemental circuit closing members carried by said listening-in key switches, contact points operating in conjunction with said supplemental circuit closing members which are carried by the listening-in key switches, and a circuit connected to said contact points and including means adapted to continually produce an audible warning signal in the subscriber's receiver when any of the listening-in key switches is in closed position and the local operator's circuit, including the transmitter and receiver, connected to the line.

Signed at New York, borough of Manhattan, in the county of New York and State of New York, this 19th day of February, A. D. 1917.

GEORGE I. GALITZKA.
